UNITED STATES PATENT OFFICE.

GABRIEL ROHRBACH, OF DEL RIO, TEXAS.

GATE-LATCH.

SPECIFICATION forming part of Letters Patent No. 466,186, dated December 29, 1891.

Application filed June 29, 1891. Serial No. 397,842. (No model.)

To all whom it may concern:

Be it known that I, GABRIEL ROHRBACH, of Del Rio, in the county of Val Verde and State of Texas, have invented a new and useful Improvement in Latches for Gates, of which the following is a full, clear, and exact description.

This invention relates to improvements in fastenings for gates, and has for its object to provide a convenient and simple device of the character named which may be readily operated to fasten or release the gate, a further object being to provide a novel latching-catch that may be adjusted toward or from a gate on a post to be engaged by the latch proper and enable compensation to be made for spreading of the posts upon which the gate is supported and to which it is secured by the latching device.

To these ends my invention consists in the peculiar construction and combination of parts, as is hereinafter described and claimed.

Reference is to be had to the accompanying drawings, forming a part of this specification, in which similar letters of reference indicate corresponding parts in all the figures.

Figure 1 is a side elevation of a gate having the improvements applied and in closed and locked position. Fig. 2 is an enlarged front elevation of a gate and an adjacent latching-post in part with the improvement thereon, the parts being also shown in locked adjustment. Fig. 3 is an enlarged perspective view of part of the upper portion of a gate, showing the improved latching device thereon. Fig. 4 is a sectional plan view of a portion of a fence-post, an improved latch-plate being shown secured thereon and engaged by the improved latching device on a gate, shown broken away and in section on the line 4 4 in Fig. 2. Fig. 5 is a broken perspective view of a post toward which the gate swings and an improved catch-plate in place on it; and Fig. 6 is a transverse section of parts of the latching device, taken on the broken line 6 6 in Fig. 2.

The improvement herein shown may be applied to any swinging gate, and is especially well adapted for use in connection with gates for yards and large inclosures.

A indicates a gate of moderate dimensions, and B and C the posts between which the gate

is designed to swing. The gate A is hung on the post C by two hinges G and G', that may be of any well - approved form. Preferably 55 said hinges are constructed to pitch the gate sufficiently so as to cause it to swing shut when free to do so.

On the upright frame-bar A' of the gate A, which represents the free vertical edge of said gate, a latching device is located, which is connected to a bracket-plate a, that is attached to the inner face of the gate-bar named, which device is constructed essentially as follows: At a proper point, vertically considered, the 65 plate a is perforated for the sliding engagement of a bolt b, that is loosely located in an enveloping case b', the latter being firmly embedded transversely in the frame-bar A' at such a point as will allow the end portion of 70 the slide-bolt b to pass through the perforation in the plate a. The bolt b is provided with a locking-lug b², that may slide in a longitudinal slot b³, formed in the case b', or, if rotatably moved away from said slot, prevent 75 the retraction of the bolt by its impinge on the end of the case b'. A rocking arm E is provided which is perforated to have a loose engagement with the inwardly-projecting end of the slide-bolt b, having contact with a radial collar b⁴ on the said bolt. (Shown in Figs. 2 and 4.) The portion of the bolt that extends inwardly through the arm E has a finger-piece b⁵ or other similar device secured on it to facilitate the manipulation of the slide-bolt 80 when this is desired. The rocking arm E is connected with the frame-bar A' of the gate by its pivotal attachment on the bracket-plate a, the latter named having two ears d formed on its lower portion, which project therefrom 85 in vertical parallel planes and are transversely perforated to receive a fulcrum-pin e, which also passes through similar perforated ears g, that are projected from the side edges of the rocking arm E and loosely embrace the ears 90 d, as shown in Figs. 2 and 6.

Between the ears d on the pin e a coiled spring h is located, which has its free ends engaged with the bracket-plate a and arm E, so as to normally project the lower portion of 100 said arm outward. Below the pivot-pin e a tripping limb i is formed on the rocking arm E, which limb projects outward and upward for convenient manipulation, affording means

to draw the bolt when the limb is rocked downward, and above the slide-bolt an outwardly-inclined portion m is formed on the rocking arm E to receive the impinge of another piece, 5 which will be described.

On the top cross-bar A^2 of the gate A , in the corner formed by the junction of the side bar A' and top cross-bar A^2 , a knee-plate n is fastened, and a vertical perforation is formed 10 therein that is extended through the top bar A^2 , in which perforation a slide-bar F is located and supported for longitudinal adjustment by the spiral spring o , which has one end secured to the bar F and encircles it, resting 15 upon a perforated bracket-block o' , through which the slide-bar passes.

Upon the lower end of the slide-bar F a laterally-projected toe r is formed, the outer edge of which rests upon the inclined portion 20 m of the rocking arm E , a knob s on the upper end of the bar F affording means to depress said bar, rock the arm E , and withdraw the slide-bolt b from its latched connection with the latching-plate D .

25 As it is desirable that the gate be secured to the post B if swung in either direction, the latching-plate D is formed with a central stop-piece t and two latch-hooks t' and t^2 , formed integrally and sloping oppositely, said plate 30 D having opposite and parallel side plates u formed on it, that extend from the outer corners of the sloping latch-hooks t' and t^2 and are each perforated to afford two rows of holes v for screws. The said plates u being so 35 spaced apart that they will embrace the opposite sides of the gate-post B are adjusted

thereon and secured thereto at such a point of lateral projection as will allow the end of the slide-bolt b to latch fast to either of the hooks t' and t^2 if the gate is opened and then 40 swung to close it. If there should be a necessity for a change of position to compensate for spreading or closing between the posts B and C , this can be readily effected, as the latch-plate D can be moved in or out on the 45 post B and be thereto secured by utilizing different screw-holes v in the side plates u .

In operation, the gate being hung on hinges that will permit it to be swung in either direction and engage the latch-bolt with the 50 catch-plate on the post B , it will be apparent that the depression of the knob s will move the slide-bolt b and detach it from the catch-plate D , and also that the vibration of the rocking arm E may be effected by a downward 55 manipulation of the tripping limb i thereon, so as to disengage the bolt b from the latch-plate.

Having thus described my invention, I claim as new and desire to secure by Letters Patent—

In a gate-latch, the combination, with a slide-bolt and a spring-pressed rocking arm engaging the bolt, having an outwardly-inclined upper end, of a spring-pressed sliding bar having a toe adapted to engage the inner 65 face of the inclined end of the rocking arm, substantially as shown and described.

GABRIEL ROHRBACH.
